INVENTOR,
Charles E. Hanny,
BY
R. S. HANNY, ATTORNEY.

UNITED STATES PATENT OFFICE

CHARLES E. HANNY, OF UNIONVILLE, CONNECTICUT, ASSIGNOR TO TRUMBULL ELECTRIC MANUFACTURING COMPANY, OF PLAINVILLE, CONNECTICUT, A CORPORATION OF CONNECTICUT.

RESIDENCE PANEL BOARD

Application filed April 21, 1928. Serial No. 271,859.

My invention relates particularly to what are commonly known as dead front panel boards and similar constructions which include a box or receptacle intended to be set into the wall and contain circuit protecting devices, such as, plug fuses.

One object is to provide a construction in which all of the electrical parts and connections are completely housed so as to prevent accidental contact or tampering.

Another object is to provide a construction of this character to which access can be readily had by authorized persons when necessary but in which all of the live wires and terminals are normally inaccessible.

Another object is to provide a construction of this character which may be readily and conveniently installed.

Another object is to provide an enclosed panel board construction, the parts of which may be readily installed from time to time as the building is being erected, for instance, so that the box may be installed, the conduits connected, and the wires run in to the empty box after which the fuse units may be added and secured in position and the cover attached.

Another object is to provide a construction in which the main cover, the fuse door and the guard member are secured together as a unit, which unit may be readily removed for inspection, wiring, or replacement of parts.

Another object is to provide a neat, cheap, and practical door and frame construction applicable to devices of this character.

Another object is to provide a construction in which an insulated guard member is secured to the main cover as a unit and in which the guard member is recessed to form a fuse chamber entirely surrounded by integral walls the edges of which also function as a rabbet for the fuse door.

In carrying out the invention in its preferred manner the main cover and door are so designed that the door with integral pivots can be stamped from the plate which is to form the cover. Separate pieces are provided to form the hinge bearings and these pieces are riveted to the cover plate in proper posi-

tions to receive the hinge pintles of the door. The guard member is formed of insulating material and secured to the back of the cover plate so as to provide a chamber for the fuse plugs and afford an abutment for the door. The guard member is provided with passages for the fuse plugs and grooves in the edges of the passages to facilitate testing.

This application is a continuation in part of my former application 99,209, filed April 2, 1926 and which has matured into Patent 1,740,862, and in which I have claimed the general construction of the panel board and particularly the fuse carrier and its adjustable relation to the box, the cover plate and the guard member.

Fig. 1 is a horizontal sectional view of the construction embodying the preferred form of my invention.

Fig. 2 is a perspective view of the cover plate with the hinged door partly open.

Fig. 3 is a perspective view of the guard member.

These two perspective views show the general relation of the guard member to the cover plate when these parts are separated.

Fig. 4 is a fragmentary front view of one corner of the cover plate with a fragment of the door in place and showing one hinge.

Fig. 5 is a corresponding view of fragments of the cover plate and door as stamped from a single sheet or plate of metal and before the hinge bearing is affixed.

Fig. 6 is a vertical sectional view showing the complete construction with the door partly open and in perspective.

Figs. 1 and 6 show fuse plugs in place.

Fig. 7 is a vertical sectional view of the cover plate and guard member with the door closed and omitting the box and fuse carrier.

Fig. 8 is an enlarged fragmentary horizontal sectional view showing the upper hinge connection for the door, the door being shown in full lines in the partly open position and shown in dot and dash lines in the fully open position.

Fig. 9 is a vertical sectional view of the same hinge bearing with the door closed.

The box 10 may be of any suitable construction in which is mounted a fuse carrier

11 which may be of any suitable construction so far as the claims herein are concerned. This fuse carrier 11 supports a number of fuse sockets 12 and may be provided with 5 any suitable circuit terminals. The fuse plugs 13 are intended to be merely typical of any suitable form of circuit protecting device.

The front plate or cover 14 for the box 10 is preferably formed of sheet steel and provided with a swinging door 15 which is normally closed and conceals the fuse plugs 13. The box 10 would, of course, ordinarily be mounted in the wall and the outer edges or 15 flange cover plate would be substantially flush with the outer surface of the wall.

The guard member 16 is formed of any suitable insulating material and is secured to the cover plate 14 by screws or bolts 17 which 20 pass through openings 18 in the cover plate and through the lugs 19 in the guard member and are provided with nuts 20 for clamping the parts together. These screws 17 are preferably not slotted but perfectly smooth on 25 their outer faces so that it is not possible to loosen them from the front.

The front cover plate is adapted to be secured to the box by a series of screws 21 which screw into lugs 22 projecting from the 20 inner wall of the box. These screws 21 are preferably loosely mounted in the cover plate and may be held from accidental disengagement by washers 23 mounted on reduced shanks of the screws so that when the screws 35 are retracted from the lugs 22 they will not fall out.

The guard member 16 is provided with passages 25 which receive the front ends of the screw shells 12 for the fuse plugs. 40 Grooves 26 are preferably provided in the sides of these passages 25 to admit testing implements.

In the manufacture of the cover members, the door members 15 are preferably punched 45 or stamped out of the same plates that form the cover members 14 and this is accomplished in the following manner: Obviously a blank of this character could not be punched out from a sheet of metal and then 50 set back into the opening and made to function as a door without some additional operation, in fact it would be very difficult to even force the blank back into the opening therefore the door is first punched out in the 55 form as indicated by the outer lines in Fig. 5, then the door blank is re-punched or trimmed so that its outline becomes practically as indicated by the inner lines in Fig. 5 in which form it is slightly smaller than 60 the opening in the cover and the pintles 30 have been trimmed to their final form.

The parts are so cut that the door has upper and lower hinge pin or pintle extensions 30 which preferably are pressed outwardly, 65 as shown in Fig. 9, so as to provide an off

set pivotal axis by means of which the door may be swung open to a plane parallel with the cover plate. The bearing members 32 are stamped from sheet metal and provided with forwardly projecting lugs 31 which receive 70 the pintles of the door and bar portions 32' and rivet portions 33 which are preferably headed over to secure the members in position. The cover plate is cut away or punched out at 34 and 35 to receive these portions 31 75 and 33. Of course, the upper and lower bearings are oppositely disposed to coact with the upper and lower pintles of the door.

The guard member 16 is provided with flanges 37 to constitute abutments for the 80 edges of the door. These flanges are cut away or grooved at 38 to accommodate the bearing members 32. The cut away portion 39 allows for the swinging of the hinged edge of the door.

The door is preferably provided with a spring catch 40, one end of which is secured to the door. The shoulder 41 coacts with the edge of the cover plate to hold the door closed. This latch member is also preferably provided with a finger piece or extension 42 to facilitate release. Preferably the cover plate is provided with a recessed portion 33 to admit the end of the finger for releasing the 90 latch.

Panel boards of this character are usually installed in more or less obscure positions in dwellings or apartments before the lighting circuit has been connected therefore the wireman is considerably hampered in his 100 work and a great advantage of my construction is that all of the cover and guard parts, including the attaching screws are completely assembled as a unit and cannot become 105 mislaid or lost and by simply loosening four screws, the wireman may remove the entire unit and may then have full access to the interior of the box for making the necessary 110 electrical connections.

An advantage of the guard member, per se, 110 is that it is formed of a single block of insulating material which rests flat against the cover member in such a manner that there can be no possible access to any of the line terminals except by removing the entire cover and guard unit. The flat abutment of the guard member against the cover makes it possible to hinge a door member in the plane of the cover member so that the edges of the 115 guard member form a rabbet for the door and no other parts or forming operations are required in order to accomplish this result.

It will be noted that the cover screws are positioned at the corners of the box in such 120 a manner that, in securing the cover to the box, it is merely necessary to set the screws into the corners, when by reason of the washers 23 and the pointed ends of the screws, the 125 screws are so positioned that they may then 130

be run into the threaded holes in the brackets without fishing for the holes.

I claim:

1. A residence panel board construction including a box, a fuse block secured in said box and having pertinent terminals and projecting fuse plug shells, a cover for said box having a fuse door hinged thereto and an insulating fuse guard member detachably secured to said cover with securing means operable only from the rear of said cover, said guard member having passages to receive and surround said fuse plug shells and having continuous integral side walls to form a recess for the projecting ends of fuse plugs and said side walls forming an abutment for the said fuse door in its closed position the parts being so constructed that when the door is open for inspection of the fuses all other conducting parts are covered, and means for detachably securing the cover and guard member to the box.
2. A residence panel board construction including a box, a fuse block secured in said box and having pertinent terminals and projecting fuse plug shells, a cover for said box having a fuse door hinged thereto and an insulating fuse guard member detachably secured to said cover with securing means operable only from the rear of said cover, said guard member having passages to receive and surround said fuse plug shells and having continuous integral side walls to form a recess for the projecting ends of fuse plugs and said side walls forming an abutment for the said fuse door in its closed position, and means for securing the cover to the box independently of the guard member, the cover and guard member being removable as a unit without disturbing the box or fuse block the parts being so constructed that when the door is open for inspection of the fuses all other conducting parts are covered, and means for detachably securing the cover and guard member to the box.

3. A residence panel board construction including a box, a cover detachably secured to said box and having a door mounted thereon, an insulating guard member detachably secured to said cover and having a recess in register with said door and also having fuse plug passages in the bottom of said recess, a receptacle mounted within said box and having fuse plug receiving shells projecting into the passages in said guard member, terminals mounted on said receptacle and adapted for direct connection with the line wires of a circuit, said guard member covering the circuit terminals when the door is open for access to the fuse plugs, the said cover and the said guard member being secured together and removable as a unit.

CHARLES E. HANNY.
